UNITED STATES PATENT OFFICE.

MORRIS GOLDBERGER, OF CHICAGO, ILLINOIS, ASSIGNEE TO CRESCO CREAMERY SUPPLY CO., OF CHICAGO, ILLINOIS, A CORPORATION OF ILLINOIS.

MECHANICAL MOVEMENT.

Original application filed February 5, 1921, Serial No. 442,738. Divided and this application filed March 8, 1922. Serial No. 541,966.

To all whom it may concern:

Be it known that I, MORRIS GOLDBERGER, a citizen of the United States, and a resident of Chicago, in the county of Cook and 5 State of Illinois, have invented certain new and useful Improvements in Mechanical Movements; and I do hereby declare that the following is a full, clear, and exact description thereof, reference being had to 10 the accompanying drawings, and to the characters of reference marked thereon, which form a part of this specification.

This invention relates to a novel mechanical movement for translating the continuous 15 rotary movement of a driving element into intermediate rotary movement of a driven element, whose axis is disposed at a right angle to the axis of rotation of the driving element.

20 Among the objects of the invention is to produce a novel mechanical movement of this character by which intermittent motion of definite increments is imparted from a continuously rotative driving element to a 25 driven element through a complete half cycle or 180 degrees of angular movement of the driving element and for holding or locking the driven element from movement throughout the other half cycle or 180 degrees 30 of angular movement of said driving element.

Another object of the invention is to produce a novel mechanical movement constructed to impart from a continuously 35 rotating driving element a uniform accelerated and decelerated movement to the intermittently operated driven element.

Another object of the invention is to produce a mechanical movement of the character described, wherein the actuator element that transmits direct movement from the driving to the driven element remains a constant distance from the axis of a member which constitutes part of the driving 40 connection between the driving and the driven elements.

Other objects of the invention are to improve and simplify mechanical movements 45 for translating continuous rotary movement of a driving part to an intermittent rotary movement of a driven part through definite increments, and for locking the driven element stationary between intervals of movement thereof, and the invention consists in

the combination and arrangement of the 55 elements shown in the drawings and described in the specification, and is pointed out in the appended claims.

A mechanical movement embodying my invention is particularly valuable for use in 60 connection with a machine in which operative parts thereof, connected to and movable with the driven element, must be operated with a high degree of uniform acceleration and deceleration from the beginning 65 of said intermittent movement to the end thereof. An instance of such use is found in an intermittently operable filling and capping machine for filling receptacles with liquids during a time when the receptacle 70 holders are in motion and for capping the receptacles during a time when the receptacle holders are stationary. Such a use of the mechanical movement is shown in my United States Letters Patent, Number 75 1,456,690, granted May 29, 1923, of which this application is a division. The mechanical movement herein disclosed, however, may be efficiently applied to other and different uses where acceleration and deceleration of speed of the part movable by the driven element is desirable.

In the drawings:

Figure 1 is a side elevation, partly broken away, of the essential elements of a mechanical movement embodying my invention.

Figure 2 is a bottom plan view thereof, with parts in section.

Figure 3 is a section on the line 3—3 of Figure 1, as viewed in the direction indicated by the arrow.

Figures 4 and 5 are diagrammatic views illustrating the operation of the driving and driven elements.

As shown in the drawings, 10 designates 75 a continuously rotative driving element, in the form of a shaft, adapted to be connected with any suitable source of power, and 11 designates an intermittently rotative shaft which is disposed at a right angle to the 100 driving element or shaft 10, and is adapted to be intermittently rotated.

12 designates a unit which constitutes a connection between the driving and driven elements. As shown it comprises a generally half spherical formation 13 and is hollow, with its open side facing downwardly and with its wall of substantial thickness.

It is formed with a hub 14 to which the shaft 11 may be attached in any suitable or preferred way. So far as the essence of the invention is concerned the unit may be of other form and said unit may be otherwise connected to the part to be operated thereby. The center 21 of the said unit is at the intersection of the axis of the hub 14 and the plane of the base 15 of the unit, which said base is disposed in a plane at a right angle to the axis of said hub. The said unit 13 being pinned or otherwise non-rotatively fixed to the shaft 11 becomes, in a broad sense, part of the driven element and is formed for operative connection to parts on the driving element, as will hereinafter appear.

The shell of said unit is provided with a plurality of angularly spaced, elongated, 20 driving recesses 16 which open through the base or rim 15 and extend principally throughout the semispherical portion thereof. The said unit is also provided with an equal number of intervening wider, but shallower, notches 17 having curved, upper walls and which also open through the base 15. Said notches 17 are located equidistantly between adjacent recesses 16. The number of said recesses and also the number of said 30 notches will depend upon the extent or angular movement or increment to be given to the intermittently driven member in each operation. As herein shown, eight of said recesses 16 are provided, spaced at 45° apart.

Fixed to the end of the driving shaft 10, adjacent to the unit 13 is a member 18 which is provided with a crank arm 19 that is disposed at an oblique angle to the axis of said shaft 10. Said crank arm carries at its 40 outer end a stud 20 disposed at an oblique angle to said arm, and whose axis is radial to the center 21. Said stud carries an anti-friction roller 22 that is held on the stud between the arm 19 and a head 23 on the inner end of the stud.

By reference to Figure 1, it will be noted that the axis of the driving shaft 10 is in the plane of the base 15 of the unit and, therefore, is radial with respect to said center 21. 50 Thus, both the axes of the said driving shaft 10 and the stud 20 are radial to said center.

This angular relation of the stud 20 relatively to the center 21 and to the axis of the driving element or shaft 10 is such that during 55 one half of the rotation of the driving shaft 10 the axis of the stud passes from the plane of the base 15, as indicated in full lines in Figure 5, upwardly into one of the recesses 16 and thence to said base through the same recess, with the recess engaged by said stud moved an angular distance of 45° in the direction indicated by the arrow in said Figure 5. It will be observed that throughout 60 the full travel of the stud 20, into and out of the driving recess 16 the stud remains

at a constantly fixed distance from the center 21, so that the effective length of the lever arm of the driving element on the driven element remains constant.

The said member 18 at the inner end of the driving shaft 10 is formed with a part cylindric faced locking extension 24, said face being concentric to the axis of the driving shaft 10. Said extension projects inwardly beyond the inner side of the crank arm 19 for engagement with the locking notches 17. In the part of said extension on the side thereof remote from its parts of cylindric or convex locking face it is formed with a concave relief surface 25. The convex side of said locking extension extends throughout 180° of a circle and is adapted for locking engagement with the walls of a shallow locking notch 17 of the unit 13 at a time when the bearing stud 20 and its roller 23 are moving through an arc of travel exterior to and out of contact with the walls of recesses 16, and, therefore, during the time when the stud and roller are passing from one said recess 16 to the next adjacent recess. The circumferential length of the convex face of the locking stud is such as to maintain its locking engagement with the walls of the locking notches 17 during the entire period while the roller bearing crank stud is passing from the open end 15 of one recess 16 to the open end of the next adjacent recess 16. This condition is brought about by the fact that the convex locking face of the extension 24 is concentric to the axis of the driving shaft 10 and also that said axis of the shaft lies in the same plane, as clearly indicated in Figure 5. The cut away portion of the locking extension, indicated by the concave line 25, provides clearance between said extension and the base 15 of the unit 13 while the driving stud 20 is moving through the operative part of its arc of travel to give intermittent angular movement to the driven part.

By reason of the fact that the axes of both the driving shaft 10 and the stud 20 are radial to the center 21 of the unit 13, and of the fact that the convex locking face of the extension 24 is moving out of a locking engagement with the wall of a notch 17 when the bearing roller 22 of the stud 20 is moving into an adjacent driving recess 16, there is no lost motion effected in transmitting driving movement from the driving shaft 10 to the driven shaft or element. Therefore, the crank stud 20 is active throughout 180° of a circle to drive the driven element with uniform accelerations and decelerations of movement. This uniform acceleration and deceleration of movement has the effect of giving to the driven part a highly smooth action and avoids jars and shocks being thrown on the parts of the movement and on the parts of the mecha- 125 130

nism which it intermittently drives. Also the parts which are intermittently rotated pass from a state of rest to movement gently and likewise pass from a state of movement to rest. A practical advantage of this intermittent driving motion, when used in connection with a filling machine of the general character mentioned, is that liability of too rapidly moving the container during the 5 intermittent, angular movements of the container holders, such as would tend to throw the material from the containers by reason of the inertia of the material or the inertia of the containers is avoided, while permitting 10 the machine to be operated with a maximum permissible capacity. This will be made clear by a consideration of the fact that such uniform acceleration and deceleration of movement and lack of sudden start- 15 and stopping of the intermittently movable container holders enables said holders to be practically moved at relatively high speed, and this condition increases the capacity of the machine. In other words, the 20 arrangement shown admits of the holders of the circular series thereof to be placed closer together, so that thereby a greater number of containers can be filled in a given time, as compared to an arrangement where- 25 in the acceleration and deceleration is not uniform and wherein the containers are started and stopped more abruptly in the intermittent movements thereof.

An important advantage of the locking 30 device shown, wherein the locking extension is a rigid or unitary part of the driving crank, is that I am able to produce exact registration between parts carried by the intermittently driven part and stationary 35 parts with which they are adapted to coact, and to hold said parts in such registration during the idle period of the driven part. Furthermore, the coacting parts of lock are formed on elements which can be made 40 amply strong and massive to hold the driven part and mechanism operated thereby accurately in such alignment.

Another general advantage of the construction shown in respect of whatever kind 45 of machine in which it may be embodied, is that mechanical shocks between the driving and driven elements are, to a maximum extent, reduced, thereby lessening wear on the contacting and bearing parts of the driving 50 and driven elements, due to large accelerations and decelerations of movement from rest to speed and speed to rest, found in mechanical movements heretofore known.

I claim as my invention:

60 1. A mechanical movement comprising a continuously rotative driving and an intermittently rotative driven element, said driven element embracing a unit having a series of angularly spaced driving recesses, 65 and the said driving element having a crank

stud to engage said recesses, the axes of said driving element and stud being radial to and intersecting the axis of the driven unit, which is in the plane of the open ends of said recesses. 70

2. A mechanical movement comprising a continuously rotative driving and an intermittently rotative driven element, said driven element having a spherical segment formation and a base, and whose center is 75 at said base, and provided with driving recesses concentric to said center and opening through said base, and said driving element having a crank stud to traverse said driving recesses, and arranged to be at all times a 80 constant distance from said center.

3. A mechanical movement comprising a continuously rotative driving and an intermittently rotative driven element, said driven element having a spherical segment 85 formation and a base, and whose center is at said base, and provided with angularly spaced driving recesses concentric to said center and opening through said base, and said driving element having a crank stud 90 whose axis is oblique to the axis of said driving element to traverse said driving recesses, the axes of the driving element and stud being radial to and intersecting said center. 95

4. A mechanical movement comprising a continuously rotative driving and an intermittently rotative driven element, said driven element having a spherical segment 100 formation and a base, and whose center is at said base, and provided with driving recesses concentric to said center and opening through said base and provided between said recesses with locking notches, and said driving element having a crank stud to traverse 105 said driving recesses, the axes of the driving element and stud being radial to and intersecting said center, and the driving element having a locking extension adapted to rotatively engage said notches when said driving stud is traveling exterior to said driving recesses. 110

5. A mechanical movement comprising a continuously rotative driving and an intermittently rotative driven element having a 115 rim, the latter concentric to its axis of rotation and formed with angularly spaced driving recesses which open through said rim, said driving element having its axis lying in the plane of said rim and having an oblique driving pin to traverse said recesses, the axis of said pin intersecting the axis of 120 said driving element at the center of the driven element.

6. A mechanical movement comprising a 125 continuously rotative driving and an intermittently rotative driven element, the latter embracing a rim concentric to its axis of rotation and formed with angularly spaced driving recesses and intermediate said driv-

ing recesses with shallow part cylindric locking notches all of which open through said rim, said driving element having an oblique driving pin to traverse said recesses, whose axis intersects the axis of said driving element at the center of the driven element and in the plane of the rim, and said driving element having an extension formed with a half cylindric face to engage said notches when said pin is released from said driving recesses.

7. A mechanical movement comprising a continuously rotative driving and an intermittently rotative driven element, the latter embracing a rim concentric to its axis of rotation and formed with angularly spaced driving recesses and intermediate said driving recesses with shallow part cylindric locking notches all of which open through the said rim, said driving element having an oblique driving pin to traverse said recesses, whose axis intersects the axis of said driving element at the center of the driven element and co-incident with the plane of said rim, and said driving element having an extension formed with a part cylindric face to engage said notches when said pin is released from said driving recesses.

8. A mechanical movement comprising a continuously rotative driving and an intermittently rotative driven element, the latter

embracing a rim concentric to its axis of rotation and formed with angularly spaced driving recesses which open through said rim, said driving element having a stud to traverse said recesses, said stud being displaced from the axis of rotation of said driving element, the axis of said driving shaft being in the plane of said rim.

9. A mechanical movement comprising a continuously rotative driving and an intermittently rotative driven element, the latter embracing a rim concentric to its axis of rotation and formed with angularly spaced driving recesses which open through said rim, said driving element having a stud to traverse said recesses, said stud being displaced from the axis of rotation of said driving element, the axis of said driving shaft being in the plane of said rim, said rim being provided intermediate said recesses with part cylindric locking notches and the driving element having a locking extension formed on one side with a part cylindric face concentric with said latter element to engage a locking notch when said stud is released from a driving recess.

In witness whereof I claim the foregoing as my invention, I hereunto append my signature this 28 day of February, 1922.

MORRIS GOLDBERGER.
